UNITED STATES PATENT OFFICE.

NICHOLAS J. WAGNER, OF CHICAGO, ILLINOIS.

ROOF-TRUSS.

1,392,096.

Specification of Letters Patent. Patented Sept. 27, 1921.

Application filed January 10, 1920. Serial No. 350,628.

To all whom it may concern:

Be it known that I, NICHOLAS J. WAGNER, a citizen of the United States, residing at Chicago, in the county of Cook and State 5 of Illinois, have invented a certain new and useful Improvement in Roof-Trusses, of which the following is a specification.

This invention relates to roof trusses, particularly wooden roof trusses. The object 10 of the invention is to provide a truss of this kind which can be easily and cheaply made, which is compact in form, which is satisfactory in operation, and not readily liable to get out of order. The invention consists 15 in many features and details of construction very fully set forth in the specification and claims.

Referring to the drawings in which like 20 numerals represent the same parts throughout the several views,

Figure 1 is a side elevation of a wooden truss supporting a roof, the same being constructed in a manner to embody the mechanism of this invention in its preferred form.

Fig. 2 is an inverted plan view of the truss proper taken on the irregular line 25 2-2, Fig. 1.

Fig. 3 is a vertical, sectional detail view, taken on the line 3-3, Fig. 1.

Fig. 4 is a detail view of one of the boards of which the upper chord of the truss is made showing the upper edge 26 curved, and Fig. 5 is the same member showing the upper edge 26^a in irregular polygonal form.

Fig. 6 is an enlarged detail side view of the end of the truss at the point where it is supported on or in the wall of the building.

Fig. 7 is a bottom view of that portion of the lower chord and attached parts appearing in Fig. 4.

Fig. 8 is a perspective view of the portions of the upper and lower chords where the joining member is separated one from the other.

Fig. 9 is a sectional end view on the line 9-9 of Fig. 4.

In constructing the roof truss of this invention, the curved upper chord designated as a whole by the numeral 10 is made up of 50 two separate laminated sections 12 of like construction placed on opposite sides of the lattice members 16 secured thereto by bolts 68 in the ordinary manner. In the particular case here illustrated, each section 12 is made up of three parallel layers 20, 21, and 22 of non-bent boards 18 placed on edge,

each board having its upper surface cut either in a true curve 24 as shown in Fig. 4 or in a polygonal form 26 as shown in Fig. 5 to conform to the general line of curvature 60 of the roof proper 50. The bottom edge 28 of each board 18 is substantially straight, while the ends 30 are at angles to the curvature of line 24-26 corresponding to the radius lines on the truss. These component 65 board members 18 of each of the three sections 20, 21, and 22 of boards are staggered with each other as clearly shown in Fig. 2 so that the joints between abutting board members of a given one of the sections or 70 integral parts 20, 21, and 22 break joint with each other in the obvious manner. The great advantage of using these board members 18 illustrated in Figs. 4 and 5 placed on edge and without bending in the process 75 of making or putting together, is that the truss, when finally completed, is without initial bending strain tending to cause it to pull itself apart as is the case in prior structures where parts strained by bending are 80 used. The truss of this construction is capable of accurate calculation as to strains, while one bent in manufacture is not. This upper chord of truss is stiffened against lateral movement by placing throughout its 85 entire length and between the side members 12, heretofore described, a stiffening member 32 in actual construction frequently a 2x4 timber, secured in place by nailing or any other ordinary obvious manner, common in 90 wood structures.

This construction so strengthens the truss of a given weight that there is greater unsupported length of chord between lattice members of the truss, thus reducing the 95 number of lattice members required, and consequently reducing the cost of the truss.

The lower chord of the truss designated generally by the numeral 34, is also made of two separated and laminated members 36 100 whose details of construction are not of importance for the purposes of this particular application. This lower chord 34 has placed between its side members 36 and adjacent to each of its ends a spacing and 105 reinforcing wooden strip or block 38 extending a sufficient distance toward the truss center so that when secured in place by bolt 40, this lower chord member is very strong and rigid at its end. The side members 36 110 of the lower chord are at their ends, preferably but not necessarily cut away in an-

gular lines 42 conforming to the curvature of the lower side 44 of the upper chord with the result that when the parts are assembled the ends of the upper chord rest 5 upon faces 42 of the lower chord and extend down to the level of the lower line 46 of the lower chord. In the particular construction here illustrated, the end of the member 32 heretofore described, enters a 10 notch 48 in or adjacent to the end of member 38 heretofore described, thus assisting in bracing the upper chord to the lower chord and helping to insure the holding of the upper chord against lateral movement with 15 reference to the lower chord under load on the roof 50 carried by the upper chord.

One of the important features of the invention is the use about this connection of the two chords of a U-shaped metal strap 52 20 lying in general in the horizontal plane of the lower chord passing around the end of the upper chord and positively secured in place by bolts 54 which pass through both sides of this U-shaped strap, both parts 36 25 of the lower chord and the central spacing member 38, heretofore referred to. These bolts 40, passing through this block 38 are very important, in that because of the central block held in place by the bolts 40, 30 heretofore referred to, it is unnecessary to carry the metal of the U-shaped member 54 back to or beyond the part of the lower chord in which the bolts 40 are located, thus reducing materially the amount of metal 35 required, and the weight to be handled, and the structure is also important in that it prevents the bolts 54 from cutting the members 36 of the lower chord 34 and thus prevents endwise movement of the upper chord.

Another important feature of this U-shaped member 52 is that it lies wholly in a horizontal plane of the lower chord of the truss, and that consequently the strain, 45 which it carries, is transmitted through it in straight lines instead of at an angle, as in prior constructions, and in the line of the horizontal chord of the truss, thus avoiding the rotary and shearing action which, 50 in prior constructions, takes place when a member like 52 is secured at an angle to the horizontal chord of the truss, and is pressed upon in an angular direction by the upper chord of the truss.

55 Another important feature of the invention is the use in connection with the strap 52 of an adjustable anchor connecting the end of the truss to the building wall 56. This anchor consists in a rotatable rod 58 60 screw threaded through any suitable sort of a bearing 59 carried in the end of member 52 and having at its outer end, a rod or plate 61 which serves the double function of bearing against the side of the wall 52 65 and of being grasped by a suitable tool for

the purpose of rotating the rod 58 in screw connection 59 to thus hold the wall in proper relation to the end of the truss. This construction prevents all trouble which, in practice, takes place when anchoring devices 70 are built into a wall.

Another feature of the invention consists in reinforcing the lattice members 16 with strips, usually boards 60, cut to conform to the lower line 44 of the upper chord of the truss and the upper line 62 of the lower chord of the truss and abutting against them as clearly shown at the points 64 and 66 respectively of Fig. 3. This building out of the chord member 16 performs the double function of properly increasing in cross section the effective areas of the chord 16 and, in providing in the angular lines 64 and 66, a locking rigidity which is not present without them when the chord members 85 are simply pivoted upon the bolts 68 of the upper chord and 70 of the lower chord.

The result of all the features of the invention described embodied in the truss as shown, makes a truss which is comparatively 90 light for its strength, which will stay rigidly in place under all conditions of use and which is generally satisfactory at a minimum amount of expense. By making the top chord overlap the end of the lower chord 95 as shown in Figs. 6 to 8, a lower end portion of truss is obtained than in prior constructions, and this correspondingly lowers the height of brick side wall required. In a job now under construction this brick saving alone is three hundred dollars.

Having thus described my invention, what I claim as new and desire to secure by Letters Patent is:—

1. A roof truss comprising a curved upper chord connected from end to end by a lower chord, the two chords connected together intermediate of their ends by lattice members, the upper chord being a laminated structure composed of a plurality of layers 110 of boards placed side by side in direct contact with each other throughout the truss length, each layer being made up of a plurality of abutting boards placed on edge and staggered with reference to each other, the upper edge of each board being curved to the curvature of the truss; the successive boards being all alike so that the whole truss can be produced by using multiples of one board and definite fractions thereof at the 115 extreme ends of the truss.

2. A roof truss comprising a curved upper chord connected from end to end by a lower chord, the two chords connected together intermediate of their ends by lattice members, 125 the upper chord being a laminated structure composed of a plurality of layers of boards placed side by side in direct contact with each other throughout the truss length, each layer being made up of a plurality of abut- 130

ting boards placed on edge and staggered with reference to each other, the shapes of the respective boards being such that they fully overlap and reinforce each other, at 5 each joint, thereby dispensing with the necessity of separate joint lapping plates.

3. A wooden roof truss having an upper curved member chord, a lower straight chord connecting the ends of the upper 10 chord member, lattice work between the two chords, the upper chord being composed of two separated side members 12, each made up of a plurality of layers of boards placed side by side in direct contact with each 15 other throughout the truss length, each layer being made up of a plurality of abutting boards placed on edge and staggered with reference to each other, the lattice members entering the upper chord between 20 said separated parts, as distinguished from abutting against the bottom of the chord, for the purposes set forth.

4. A wooden roof truss having an upper curved member chord, a lower straight 25 chord connecting the ends of the upper chord member, lattice work between the two chords, the upper chord being composed of two separated side members 12, each made up of a plurality of layers of boards placed 30 side by side in direct contact with each other throughout the truss length, each layer being made up of a plurality of abutting boards placed on edge and staggered with reference to each other, the lattice 35 members entering the upper chord between said separated parts, as distinguished from abutting against the bottom of the chord,

said lattice members, however, stopping short of the top of the chord and abutting against a solid spacing member 32 extending along the length of the chord. 40

5. In a device of the class described, an upper chord and a lower chord of the truss, each made up of separated members, lattice members between the separated members of 45 each chord extending in opposite directions toward the other chord and a reinforcing board for each lattice member attached thereto and angularly bearing at its ends against its adjacent faces of the chord, for 50 the purposes set forth.

6. In mechanism of the class described, a roof truss having separated upper and lower chords, each chord being made of two laterally separated members, two angularly 55 disposed lattice members attached to one chord at a common pivotal point between the separated members of said chord, extending in different angular directions to the opposite chord occupying the entire 60 width of the space between the separate parts of the chord and a reinforcing plate 60 for one of said lattice members rigidly attached to its side and having angular ends 64 and 66 bearing against opposite faces of 65 the opposite chord, for the purposes set forth.

In witness whereof I have hereunto subscribed my name in the presence of two witnesses.

NICHOLAS J. WAGNER.
